DRAG BUCKET

Jesse F. Yaun, Baton Rouge, La.

Application February 11, 1932. Serial No. 592,378

7 Claims. (Cl. 37—135)

This invention relates to drag buckets and more particularly to an improved drag bucket construction which can be made out of relatively light material which is welded together.

An object of this invention is to provide a drag bucket structure which can be made out of relatively light sheet metal suitably reinforced so that a relatively large bucket can be provided which in itself is not unduly heavy.

10 Another object of this invention is to provide a drag bucket construction wherein the component parts thereof are welded together and the forward portion of the bucket suitably reinforced and made heavier than the rear portion so that the forward end which receives the most wear will be properly reinforced and will be able to withstand the hard usage to which a bucket of this kind is subjected.

20 A further object of this invention is to provide a drag bucket of this kind which is so constructed that it is not necessary to provide digging teeth so that the bottom thereof will dig out the desired material.

25 A still further object of this invention is to provide a bucket of this kind which is so formed that the material removed by the bucket will be easily discharged therefrom without the necessity of bumping or pounding the rear portion thereof against an object so as to dislodge material which 30 might stick in the interior of the bucket as is now the case.

The above and various other objects and advantages of this invention will in part be described in and in part be understood from the following 35 detailed description of the present preferred embodiment, the same being illustrated in the accompanying drawings, in which:—

40 Figure 1 is a detail side elevation of a drag bucket constructed according to the preferred embodiment of this invention;

45 Figure 2 is a longitudinal section taken substantially through the longitudinal center of the bucket;

50 Figure 3 is a detail front elevation of the bucket;

55 Figure 4 is a diagrammatic view showing the method of fabricating the bucket from sheets of metal;

60 Figure 5 is a detail side elevation of a modified form of the bucket;

65 Figure 6 is a sectional view taken on the line 6—6 of Figure 5;

70 Figure 7 is an enlarged fragmentary sectional view showing the manner in which the basket-

like rear portion of the modified form of the bucket is attached to the forward end thereof.

Referring to the drawings wherein like numerals of reference designate corresponding parts throughout the several views, and more particularly to Figures 1 to 4 inclusive, the numeral 10 designates generally the body portion of a bucket constructed according to the preferred embodiment of this invention. This body 10 comprises a bottom 11, side walls 12 and a rear wall 13. These parts 11, 12 and 13 are formed out of relatively light sheet metal, the sides having the lower edge portions thereof curved inwardly, as at 14, and the back is curved forwardly as at 15. The abutting edges of the sides and bottom are secured together by welding, as at 16, and in like manner the abutting edges of the bottom and the back are secured together by welding, as at 17. The bottom 11 is depressed or bent downwardly at the forward end thereof, the central portion 18 being substantially horizontal while the outer edges 19 are bent upwardly. In this manner, the forward end of the bucket is below the body and constitutes a digging means for digging the material as the bucket is dragged along the bottom of the river.

A reinforcing hood, generally designated as H, is disposed about the forward end of the body 10, this hood being welded along the marginal edges thereof to the body 10 as at 20, and the forward end of the forward lower end of the hood H is cut away, as at 21, and the bottom of this cut away portion is projected forwardly, as at 22, so as to provide a digging mouth portion which is disposed forwardly of the forward end 23 of the bottom 11.

This hood H projects upwardly above the upper edge of the sides 12, as at 24, and a curved plate 25 has the abutting edges thereof welded, as at 26, to the upper edges of the extensions 24. This extension or curved plate 25 has its forward edge substantially in alignment with the forward end of the bucket.

A plurality of reinforcing members comprising L-shaped angle bars 27 are welded, as at 28, to the cover plate 25 and to the outer surface of the hood H, the opposite ends of the reinforcing members 27 extending downwardly along the sides of the hood H and below the upper edge of the sides 12. These angle bars 27 are mounted in pairs which abut each other in order to form a substantially T-shaped reinforcing member, the two parts of which are not only secured to the hood H but are secured together as at 29.

Between the forward pairs of these reinforce-

ing members 27, there is positioned a pair of L-shaped plate members or brackets 30 each having one leg thereof welded to opposing legs of the reinforcing members 27 while the other leg of each of these members 30 is substantially vertical and extends above the vertical legs of the reinforcing members 27. The vertical legs of the bracket members 30 are provided with suitable holes or apertures 31 within which a suitable clevis or other lifting means may be mounted for assisting in the lifting of the bucket after it has been filled.

A substantially U-shaped clevis 32 is secured one on each side of the bucket at the forward end thereof with a portion projecting forwardly of the bucket for receiving an end portion of a cable to drag the bucket along the bottom of a river or the like. This clevis 32 may be secured to the side wall of the bucket by means of rivets 33 or other securing means.

The bottom of the bucket is provided with a plurality of runners 34 which extend rearwardly from the rear of the hood H and are continued upwardly along the back. These runners constitute a bottom reinforcing means and are secured to the bottom and the back wall 13 by means of welding 35 or the like. The forward ends of the runners 34 are preferably butt-welded to the rear edge of the hood H.

The sides and back 13 are also provided with inner and outer reinforcing members 36 and 37, respectively, to prevent buckling or bending of the sides and the back and the upper ends of the runners 34 are welded to the abutting edge of the outer reinforcing member 37. The forward ends of the outer reinforcing member 37 are welded to the rear edge of the hood H. The sides 12 are provided with brackets B which are secured to the outer surface thereof at a point rearwardly of the longitudinal center of the bucket and a suitable clevis or other lifting means may be engaged with these brackets B so as to cooperate with the brackets 30 in lifting the bucket after it has been filled.

In the dumping of the bucket, the lifting means attached to the brackets 30 may be released thereby permitting the tilting of the bucket which is supported by the lifting means engaged with the brackets B. The outer portion of each bracket B is provided with a square hole, as at 38, whereas the inner portion is provided with a round hole, as at 39, so that a suitable pin or trunnion may be mounted in the bracket to which the desired lifting means may be attached.

In Figure 4, there are disclosed the several sheets of metal of which the body of the bucket herein disclosed is constructed showing the manner in which these sheets are initially formed and bent prior to the welding thereof, so as to form the body of the bucket. As disclosed in this Figure 4, the bottom 11 has the forward end thereof adjacent the sides cut on a forwardly converging angle, as at 40, and the adjacent side edges are bent upwardly on a slight angle, the angle however terminating in a flat rear end portion as at 41, which is attached by welding to the forward end portion of the back 13.

As shown in Figures 5, 6 and 7, the bucket 10' has the body thereof constructed of strips of metal mounted in parallel relation to each other so as to form a substantially web-like or basket body from which the water may readily drain as well as any relatively fine material so

that any coarse material in the form of stones or rocks will be removed by this bucket.

This body 10' has the bottom thereof constructed of parallel strips 42 which are secured together by horizontal strips 43 which have the abutting ends thereof secured to the confronting edges of the strips 42. These strips 42 are continued along the bottom and are bent upwardly, as at 44, so as to form the back of the bucket. The upwardly extending strips 44 are secured to each other by means of strip members 45 which are welded to the confronting edges of the strips 44 in the same manner as the strips 43 are secured by welding 46 to the strips 42.

The side walls of the body 10' are constructed of parallel strips 47 secured together by means of connecting bars or strips 48, the opposite ends of which are secured to the confronting strips 47 by means of welding 49 or the like. The forward ends of the side strip members 47 overlap the rear end portion of the hood H' being secured thereto by means of welding 50. The upper edge or rim of the body 10' is formed of a single strip of metal, as at 51, the forward ends of which overlap the hood H' and which are secured to the hood H' by means of welding 52 or the like. Connecting bars 53 connect the reinforcing edge members 51 with the side wall members 47.

Brackets B' are secured to the side members 47 by means of securing members 54. These bracket members B' are similar in construction to the bracket members B and further description thereof is believed unnecessary. The forward ends of the bottom strip members 42 abut the rear edge of the hood H' and are secured thereto by means of welding 55 and a reinforcing plate or strip 56 overlaps the inner surface of the hood H' and the forward end of the bottom bars 42 and is secured to the hood H' and the bottom bars 42 by means of welding 57 or the like.

The hood H' has a curved plate 25' secured thereto by means of welding, the welding engaging the abutting edges of the plate 25' and the upper edges of the hood H'. Reinforcing angle members 27' are secured to the plate 25' and the hood H' by welding and a pair of L-shaped plates or brackets 30' are secured between a pair of these reinforcing angle bars 27'. A clevis engaging plate 58 is secured to each side of the hood H' below the angle bars 27' and this plate 58 projects forwardly of the hood H' and is provided with suitable holes 59 for receiving a clevis or an end portion of a cable for dragging the bucket along the bottom. This hood H' has the lower end thereof rearwardly curved and this curved portion terminates at the bottom in a forwardly projecting digging member 60 which is adapted to initially engage the bottom for forcing the material into the body of the bucket.

It will be noted from the drawings that the several forms of drag buckets herein disclosed may be readily constructed of suitable material in the form of sheet metal or bar metal which can be appropriately formed and welded together at the joints so that any desired size of bucket can be constructed without providing undue weight in the bucket itself.

In the use of this device, the dragging cable may be attached to the clevis 32 and after the bucket has been lowered to the bottom of a river or other water, the bucket can be dragged along

the bottom. Due to the forwardly and downwardly inclined bottom portion provided, the bucket need not have additional digging teeth such as are provided with grab buckets or other dredging means and when the material has been loosened by the forward edge of the hood H, the material will be forced into the body 10 and retained therein until the bucket has been lifted out of the water and dumped by releasing the cable attached to the bracket members 30.

The buckets herein disclosed are constructed in tapering form with the small end rearwardly so that when the forward end or mouth is lowered, the material will readily be discharged by gravity and eliminate the necessity of striking the rear end of the bucket on an object to loosen the material.

It is, of course, understood that various changes and modifications may be made in the details 20 of construction and design of the above specifically described embodiment of this invention without departing from the spirit thereof, such changes and modifications being restricted only by the scope of the following claims.

25 What is claimed is:—

1. A drag bucket as set forth comprising a body open at the top and front end, said body comprising side, bottom and end members formed of parallel strips, means disposed between the strips 30 for securing the strips together to form a perforate body, a hood secured to the forward ends of the side and bottom strips, said hood having the forward lower edge portion thereof inwardly and forwardly offset to provide a digging means, a 35 plurality of angle braces secured to the top of the hood in pairs to provide T-shaped braces extending over the top of the hood and terminating below the upper edge of the sides, a bracket secured between a pair of said braces at the top of the hood, and brackets secured one on each side of the side walls of the body at a point rearwardly 40 of the transverse center.

2. A drag bucket as set forth comprising a body open at the top and front end, said body comprising side, bottom and end members formed of parallel strips, means disposed between the strips for securing the strips together to form a perforate body, a hood secured to the forward end of the side and bottom strips, and means extending 45 across the top of the hood to permit lifting thereof.

3. A drag bucket comprising a body open at the top and front, an arcuate plate secured at each end to the upper edges of the sides of the bucket adjacent the front thereof, a bracing 55 means extending about the plate and downwardly over the sides, means for securing the bracing means to the sides and the plate, said bracing means comprising a pair of L-shaped angle bars, and means for securing the bars in abutting relation to each other with the leg of one bar abutting against the leg of another bar to form a T-shaped bracing means disposed in inverted relation over said plate and sides.

65

70

75

4. A drag bucket comprising a body open at the top and front, an arcuate plate extending upwardly from the sides adjacent the front of the bucket, the ends of said plate abutting against the upper edges of the sides, means for securing the abutting ends of the plate to the upper edges of the sides, a pair of T-shaped bracing members disposed in inverted relation on said plate, said bracing members extending downwardly over the sides of the bucket, means for securing the bracing members to the plate and the sides to form a substantially integral construction, said bracing members comprising angle bars disposed with the leg of one bar abutting against the leg of another bar, means for securing the abutting legs of the angle bars together to form a substantially integral T-shaped bracing member, and means disposed between said pair of bracing members whereby a flexible member may be attached to the bucket.

5. A drag bucket as set forth comprising a body open at the top and front end, said body comprising a sheet of metal formed of integral sides, bottom and rear end members, a hood engaging the outer surface of the sides and bottom and extending rearwardly of the forward end thereof, means for securing the hood to the sides and bottom, a pair of angle braces secured to the hood in abutting relation to each other and extending over the top and along a portion of the sides there- 105 of below the upper edge of the body sides.

6. A drag bucket as set forth comprising a body open at the top and front end, said body including metal sheets having their abutting edges welded together to form an integral body, a hood surrounding the forward end portion of the body and extending over the open top thereof, means for securing the hood to the sides and bottom, a plurality of angle braces extending over the top of the hood and terminating at a point below the upper edge of the side members, means for securing said angle members together in pairs to form T-shaped braces, and a bracket positioned between confronting braces and disposed at the top of the hood.

7. A drag bucket as set forth comprising a body open at the top and front end, said body including side, bottom and end members constructed of sheet metal, means for securing the abutting edges of the sides, bottom and end members together to form an integral body, a hood surrounding the forward end of the body and terminating inwardly of the forward end, a plurality of L-shaped bracing members extending about the hood, means for securing pairs of said bracing members together to form T-shaped bracing members, and runners secured to the bottom and extending longitudinally thereof, said runners being extended upwardly along the end member to provide bracing means for the end member.
